LIGHTING FIXTURE

John G. Raben, Chicago, Ill., assignor to Sears, Roebuck and Co., Chicago, Ill., a corporation
of New York

Application April 16, 1949, Serial No. 2,074

Term of patent 7 years

(Cl. D48—23)

To all whom it may concern:

Be it known that I, John G. Raben, a citizen of the United States and a resident of Chicago, in the county of Cook and State of Illinois, have invented a new, original, and ornamental Design for a Lighting Fixture, of which the following is a specification, reference being had to the accompanying drawing forming a part hereof wherein Fig. 1 is a perspective view of a lighting fixture embodying my new design, and Fig. 2 is a sectional view taken approximately along the line 2—2 of Fig. 1.

I claim:

The ornamental design for a lighting fixture as shown.

JOHN G. RABEN.
